TREATING METAL STRIP

George M. Croft, Pittsburgh, Pa., assignor to
 Blaw-Knox Company, Pittsburgh, Pa., a corporation of New Jersey

Application February 17, 1940, Serial No. 319,475

8 Claims. (Cl. 134—9)

This invention relates to procedure and apparatus for cleaning moving metal sheets, strip, or wire to remove grit, dirt, grease, scale, and other impurities.

Such cleaning is usual as a treatment preparatory to enameling, lacquering, galvanizing or otherwise plating, or other use that requires clean sheets. The invention is particularly concerned with the conservation of chemicals used in cleaning solutions and of heat applied during the cleaning processes. The invention also aims to secure an arrangement of apparatus by which strip or other articles undergoing treatment may be moved at higher speeds than have been practicable hitherto. This is accomplished by avoiding bends or turns in the direction of motion of the strip. Heretofore the practice has been to deflect the strip downwardly into, beneath the surface level of, and upwardly out of the cleaning solution; this tends to limit the speed or rate of movement of the strip.

I have determined that the strip delivered to the cleaning apparatus commonly has not only non-uniformly distributed grease and oil on its surface, but also grit and dirt. The practice has been to pass the strip directly to the hot caustic cleaning solution; thus, the caustic or other solution must be supplied in sufficient quantity to remove all loose as well as adhering grease and oil. Some grit and dirt tends to adhere so strongly that the solution fails to remove it, and the strip passes through imperfectly cleaned. In accordance with the present invention, I lessen the burden on and increase the effectiveness of the cleaning solution by preliminarily removing a large part of the dirt and grit and much of the grease and oil before the strip is introduced into the caustic solution. Although a preliminary water wash per se is not new, the applicant employs a previously used dilute cleaning solution preliminary wash and other new features which will be fully described herein.

When the strip emerges from the cleaning solution, it carries with it on both sides a film of the solution that may be several thousandths of an inch in thickness. Since the strips are often three feet or more in width and move very fast, the solution carry-over becomes large, and thus, carry-over presents an important problem. Heretofore the carry-over film has been removed by washing and the cleaning chemicals wasted, with a consequent depletion of the cleaning solution; as a result, new chemicals were required to compensate for the loss or waste.

By reducing waste of chemicals, the invention

makes it commercially practicable to employ more expensive ingredients than could otherwise be used.

These and many other objects of my invention will appear to those skilled in the art from the drawings, the specification, and the claims.

In the drawings chosen for illustrating the principles and ideas of my invention:

Figures 1A, 1B, and 1C, considered in their respective order from left to right, are vertical views in elevation and in partial section of a complete layout or arrangement for treating continuous strip;

Figures 2A and 2B, likewise considered respectively from left to right, are reduced top plan views somewhat diagrammatically showing the apparatus arrangement or layout of Figure 1A, B, and C.

Although for the purposes of illustration, I have shown a layout utilizing and providing strip in coil form, it will appear that the invention is not limited in employment to interrupted lengths of strip, as the apparatus is laid out for continuous treatment. In the arrangement shown, metal strip 5 is moved to the right from an uncoiler 6, and is initially threaded through cleaning apparatus by endless cable means 10. When the end of the first coil is reached, to continue the operation, after trimming with a down-cut shear 8, the leading end of a new coil is welded to the trailing end of a used coil by apparatus 9, thereby providing a continuous succession of strip lengths.

A pinch roll unit 11 grips the strip after it has been treated by the cleaning apparatus of the present invention and pulls it with sufficient force to draw it through apparatus located beyond the uncoiler 6, overcoming resistance offered by guide rolls, friction, scrubbers, cleaning jets, and other retarding influences. The strip is moved in a longitudinal, substantially straight-line, horizontal path or plane, and subjected to only enough deflection to insure its proper guidance, to provide uniform stresses within any transverse sectional portion, and to support it during scrubbing operations.

The strip then passes, as shown, with slack into a drag roll unit 12, is severed at the splice or weld by a down-cut shear 13 and is coiled by unit 14, see Figure 10.

The specific apparatus represented by numerals 6 to 14, inclusive, has been shown somewhat diagrammatically, as the uncoiling, shearing, welding, motivating, pulling, and recoiling apparatus illustrated is conventional. It is shown for the purpose of making clear the position of the parts

embodying the invention with relation to these parts in the cleaning stand as a whole, and as no details of these parts are claimed further description of them is unnecessary. Applicant also contemplates employing suitable conventional brushing devices, rollers, blowers, and other apparatus well known to the art, though the general arrangement thereof is new.

For convenience of illustration, the cleaning or treating apparatus is indicated generally by letters A to E, inclusive. In accordance with the present invention, the strip 5 is moved, while being subjected to successive treating applications, in continuous progression through treating chambers A, B, C, D, and E.

In accordance with a preferred procedure, the strip 5 is cleaned and scrubbed on both sides with a previously-used hot water wash solution, applied in any suitable manner, as through jets 34. The scrubbing may be done by metal brushes 32 backed by rollers 30. After being scrubbed the sheet is rinsed by a high pressure spray applied through jets 36. This rinse water also has been previously used as rinse water at the other end of the line. After passing jets 36 the strip passes between hot air blast nozzles 38, which remove most of the film of rinse water (all in chamber A) before the strip is subjected to chemical treatment in chamber B. In this manner, the amount of cleaning load required in chamber B is lessened and a carry-over of water from chamber A is prevented. The solution may be applied under a lower pressure at 34 than at 36. The purpose of jets 34 is to wet the strip being scrubbed, that of jets 36 to rinse as thoroughly as practicable. After the hot water washing operation, if used (for it may be optional), the strip is subjected to a chemical cleaning operation. The nature of the chemical reactions which take place during this operation depends upon the use to which the strip is to be put later. For pickling, acid solutions are used; for the removal of grease, hot alkaline solutions are conventional. I will describe the invention in detail as applied to any hot caustic solution.

In chamber B, the strip is subjected to what may be termed a "concentrated" cleaning solution, such as an alkali. This is applied to both sides of the moving strip through conduits 43 into a space confined above and below by casings 45 and 45a, the strip emerging through constricted slot-like openings 46. After this treatment the strip may be scrubbed by brushes 52 that cooperate with rolls 50 while covered by concentrated solution supplied by jets 54. Before leaving chamber B, the strip is washed off with a high pressure spray 56 of a diluted solution to lessen the carry-over of the expensive cleaning solution into chamber C. Drying by evaporation is inadvisable as the chemicals employed will be left on the strip. The film of concentrated solution is replaced by a film of dilute solution before the strip 5 leaves chamber B; provision is also made for collecting and employing the washed off solution to replenish concentrated solution lost by evaporation, etc.

In chamber C, a pair of rolls 60 cause the major portion of the solution film remaining to flow off sideways; provision is made for returning this solution to the concentrated solution. The liquid film that passes the rolls is further diluted and washed off by applications at 56a of dilute solution, then with clean hot water (see jets 56b); a second pair of rolls 60a removes most of the dilute

solution remaining as a film before the strip enters chamber D.

In chamber D the strip is again subjected to a series of clean hot water applications 56c; thence, 5 a pair of rolls 60b removes a large part of the liquid film, having the consistency of practically pure water, before the strip enters chamber E.

In E, the clean strip is passed between hot air blasts 67a, 67b, and roll pairs 60c to blow off all 10 possible of the remaining water and to finally dry the strip.

As shown, the treating chambers are provided with enclosing hood portions 28 having inspection doors 21, and vents 22.

15 The chambers A to E have suitable liquid collector tanks positioned therebeneath, into which liquid from the strip drains, the strip as a whole never being submerged below the liquid level in any tank. Tank 42 is under chamber A; tank 58 is under chamber B; tank 62 is under a left-hand portion and tank 63 is under the remainder of chamber C; and, tank 64 is under chamber D. I have also shown a hot water container 72 having a settling compartment 71 and a concentrated solution container 73 having a settling compartment 71a. Heat exchangers H1 to H4 and motor driven pump units M1, P1 to M6, P6 are employed to circulate and heat-condition the cleaning fluids or liquids. Valves for adjusting 20 and closing off liquid sprays or jets are indicated by the general designation a, and valves in liquid lines for the most part have been given the general designation b.

25 The circulation system is connected to effect maximum utilization of chemicals involved, and of heat applied to the treating solutions. A steam supply line 83 receives steam from any suitable source such as a boiler, not shown. It will be noted that this line 83 which enters the 30 system as shown in drawings 1B and 1C, is connected to heat exchangers H1, H2, and H3. Steam from the same or other source (through connections not shown) is preferably used as a heating means in the air heaters 39 and 68. Condensate from these heaters as well as heat exchangers H1, H2 and H3 is delivered to condensate line 91. Connections from the heat exchangers H1, H2 and H3 to this line only are shown at 108, 94, and 90 in Figure 1B. As shown 35 particularly in Figure 1A, condensate in line 91 is delivered beneath the liquid level in containers 71 and 72 through suitable nozzles or outlets d. I utilize condensate from the air heaters such as 39 and 68 which are connected by branch lines 91a and 91b, see Figures 2A and 2B, to a main line 91 which, in turn, is connected by line 90 to heat exchanger H3, and by line 94 to heat exchanger H2. The addition of this hot condensate to the preliminary wash water keeps the 40 supply thereof hot and compensates for heat lost after the first use of the same water in unit D.

45 Clean plant supply water is introduced through the piping 86. This water is continuously used for rinsing the strip in unit D, and occasionally, whenever desired to wash down the empty tanks 71, 71a, 72 and 73, as a spray against the sides of these tanks. As shown in Figure 1A, 86 is provided with suitable outlets or nozzles c that introduce washdown water as needed in spray form against the walls of hot water container 72 and concentrating solution supply container 73 through open top portions thereof; the line 86 50 has a branch line 88 that supplies water to the

same tanks and to tanks 71 and 71a at a lower level through nozzles or outlets e.

Wash water for the upper and lower spray units 34 in the chamber A is supplied through branch 35 and line 75 by pump P1 under a suitable relatively low pressure which takes the water from the hot water container 12 through a line 98. Line 75 is provided with a branch line 16 that opens into collector tank 42 at a point representing a desired level of fluid therein. Thus, a suitable amount of wash water may be bled off from the supply line 75 to keep the liquid in tank 42 at a desired level.

The wash water (preferably hot) contains some of the chemical solution for reasons which will hereinafter be apparent; and, is collected in tank 42, drains by gravity through line 77 into settling container 71 that is separated by a baffle f from the wash water supply container 12. Grease and dirt carried by the liquid from the strip are removed by employing a conventional skimming and settling means well known to the art and thus not shown. It will be apparent that the water collected in container 71 after it has been skimmed, etc., falls over the baffle f into the hot water supply container 12.

To prevent overflow and to maintain suitable liquid levels within compartments 12 and 13, I have provided an overflow pipe 99 adjacent partition g that discharges into a sewer and that is provided with two branches 99a and 99b that are connected to the compartments 12 and 13 at a point representing the desired liquid level.

The hot water supplied to the jets 34 of compartment A is supplied by line 104 from tank 64 that is positioned beneath compartment D and collects wash water that has been applied to the strip therein through nozzles 56c. It is also apparent that the actual water that is used in compartment A by nozzles 34 may have been used several times by the same nozzles, losses, of course, being made up by the supply from the line 104.

As previously pointed out, relatively pure hot wash water is supplied under relatively high pressure to nozzles 36 in compartment A through line 78 by pump P5 that is directly supplied with once-used wash water of compartment D through gravity flow line 80.

The concentrated cleaning solution, which may consist of an alkali, is supplied by container 13. In addition to liquid constantly being supplied to this container 13 from settling container 71a over baffle h after suitable conventional means, not shown, has been utilized for settling and skimming off impurities which are carried by the solution from the treated strip, make-up solution is taken from tank 63 (under compartment C) through line 103; a valve 86c connected in this line is provided with a float 87 which automatically supplies liquid make-up in accordance with the demand. Concentrated solution applying apparatus 43 and 54 of compartment B are supplied with liquid through branch lines 44 and 55 and trunk line 79. Liquid falling by gravity from the strip into collector tank 58 is pumped by pump P2 through line 80 and heat exchanger H1 to this trunk line 79. The liquid in tank 58 is maintained at a desired level by a take-off line 100 connected to a concentrating solution container 73 and pumped therefrom by pump P3 through line 101; the supply through line 101 is automatically controlled by a valve 86a that is operated by a float 87a operably positioned within the tank 58.

Concentrated solution liquid collected in tank 58 also flows by gravity through line 102 into settling container 71a, and from the lefthand tank 62 of compartment C, into the same line 102 and thence, into the same settling container.

The high pressure spray 56 of compartment B and sprays 56a of compartment C are supplied with solution which has drained from strip 5 into collecting tank 63 of compartment C, through gravity line 84, by a pump P4 which moves the liquid through line 83 into a heat exchanger H2 and thence into supply line 82. The tank 63 is provided with an outlet connection 105 entering the tank at a point representing the desired liquid level and having a valve controlled branch 106 connected at a lower point to the tank for discharging surplus or overflow material to the sewer as indicated. The level in tank 63 is further maintained by a float 87b that operates valve 86b which controls the liquid supply to the righthand spray units 56b of compartment C.

Clean rinse water is supplied to the last set of nozzles 56c in compartment D by a line 85 which is connected to heat exchanger H3. The steam line 93 is connected to heat exchanger H3 to suitably heat the rinse water supplied to 85. Water is supplied to line 85 directly from the clean water supply line 86 through line 87 by pump P6 which forces the water through line 88 into the first heat exchanger H4 and from there through line 89 into the heat exchanger H3. The condensate from heat exchanger H3 drains through connection 90 and line 91 to the preliminary hot wash-water tanks as previously described.

From the above detailed outline of the operative connections of the liquid flow circuit employed, it will be apparent that I have been able to effect a maximum utilization of heat applied to any portion of the liquid, of the liquid itself, and of chemicals utilized in forming a suitable solution with such liquid. The first treatment unit to the left of compartment A employs wash water that may contain some solution and that has been used and reused. The second or high pressure spray 36 of the same compartment employs once used wash water which is taken from the last compartment D. This compartment D is supplied with fresh cleaning water and thus the water supplied by nozzles 36 is, in effect, once used wash water. Concentrated treating cleaning solution is then applied to the strip in compartment B. This solution is used and reused and supplied with make-up water and chemicals as needed to take care of any losses. The make-up water is supplied continuously by sprays 56b, to the dilute solution tank 63, and thence, after picking up chemicals rinsed from the strip, to the concentrated solution tank 58 by sprays 56. That is, maximum utilization is made of the principle of collecting and reusing the stronger portions of the treating solution for revitalizing the original solution.

The main or initial fluid supply to compartment C is effected through the righthand nozzles 56b which are supplied directly from the fresh water plant supply line 86 after being suitably heated by heat exchangers H3 and H4, in the same manner as the nozzles 56c of compartment D. The water supplied by nozzles 56b in compartment C is collected in tank 63, reheated by heat exchanger H2 and reused again and again by nozzles 56a. As will be noted particularly in Figure 1B, the heat exchanger H1 is employed to maintain the temperature of the chemical

treating solution in compartment B at a suitable value.

Pumps are used throughout for supplying the various spray or nozzle units with cleaning or treating fluid under suitable pressure while gravity flow is used wherever possible for return lines.

The plant layout chosen for the purpose of illustrating my invention does not limit the scope of the invention which is believed to involve many novel features such as those early enumerated herein, in that the present arrangement is subject to modification and some rearrangement and may use other specific apparatus without departing from the spirit and scope of the invention as indicated by the appended claims.

I claim:

1. In a method of treating metal strip, the steps of washing and scrubbing the strip with a previously-used washing fluid, rinsing off the washing fluid by an application of a cleaner washing fluid, drying the strip, chemically cleaning the strip with a concentrated cleaning solution, removing the concentrated cleaning solution by an application of a dilute cleaning solution, and conserving the dilute cleaning solution and using it in the make-up of concentrated cleaning solution.

2. In a method of treating metal strip, the steps of subjecting both sides of a moving strip to chemical action of a strong cleaning solution; removing the film of strong cleaning solution that adheres to the moving strip by an application of and a replacement with a film of dilute cleaning solution, and returning said removed strong solution to its source of supply for re-use; replacing the film of dilute cleaning solution by an application of and a replacement with a film of wash-water, and conserving said replaced dilute solution for re-use and for replenishment of said strong solution.

3. In the cleaning of strip metal, the steps of moving the strip in a substantially horizontal plane through an initial scrubbing, rinsing and drying operation, whereby to eliminate loose particles and more easily removed surface contaminations and leave the surface thereof relatively free of liquid, thereafter applying concentrated treating liquid to the surface, the freeing of the strip from moisture by the preceding drying step conserving the treating liquid from dilution, removing most of the concentrated treating solution from the surface of the strip and diluting the residual film which remains on the strip with a second solution to conserve the chemical in the said residual film, collecting most of the weaker solution so used and which has been rendered more potent by reason of being so used for re-use, subsequently removing the residual film of dilute solution on the strip with water and conserving and re-using the water so employed.

4. In the cleaning of strip metal, the steps which comprise moving the metal in a substantially horizontal plane through a succession of treating stations, mechanically scrubbing the strip in the first of said stations, immediately thereafter rinsing the strip, drying the strip, applying a concentrated chemical solution to the dried surface of the strip and removing from the surface of the strip most of the concentrated solution so used, thereafter spraying the strip with a more dilute chemical solution to wash off the residue of concentrated solution remaining on the strip, collecting the liquid that results from the application of the dilute solution to the strip and utilizing it for the preparation of

the concentrated solution, thereafter rinsing the strip with water and utilizing some of the water so used for rinsing the strip in said first rinsing operation.

5. In the cleaning of strip metal, the steps which comprise moving the metal in a substantially horizontal plane through a succession of treating stations, mechanically scrubbing the strip in the first of said stations, immediately thereafter rinsing the strip, drying the strip, applying a concentrated chemical solution to the dried surface of the strip and removing from the surface of the strip most of the concentrated solution so used, thereafter spraying the strip

15 with a more dilute chemical solution to wash off the residue of concentrated solution remaining on the strip, collecting the liquid that results from the application of the diluted solution to the strip and utilizing it for the preparation of 20 the concentrated solution, thereafter rinsing the strip with water and utilizing some of the water so used for rinsing the strip in said first rinsing operation, and utilizing other of the rinse water so used for the preparation of the dilute solution.

25 6. In the cleaning of strip metal, the steps which comprise moving the metal in a substantially horizontal plane through a succession of treating stations, mechanically scrubbing the

30 strip in the first of said stations, immediately thereafter rinsing the strip, drying the strip, applying a concentrated chemical solution to the dried surface of the strip and removing from the surface of the strip most of the concentrated 35 solution so used, thereafter spraying the strip with a more dilute chemical solution to wash off the residue of concentrated solution remaining on the strip, collecting the liquid that results from the application of the dilute solution to the

40 strip and utilizing it for the preparation of the concentrated solution, thereafter rinsing the strip with water and utilizing some of the water so used for rinsing the strip in said first rinsing operation, said rinse water and solutions being heated, the heat being also conserved through 45 the said re-use of the liquids.

7. In the treating of strip metal to prepare it for the reception of a coating, the steps which comprise moving the metal strip in a substantially horizontal plane, and subjecting the strip while moving in this manner to a succession of operations performed in sequence as follows: mechanically scrubbing the strip on both sur-

50 faces with hot water to remove solid particles and easily removed surface contaminations, drying the strip to prevent the carry-over of a film of water beyond the drier, applying a relatively strong chemical solution to both surfaces of the moving strip to remove impurities and surface contaminations not removed by the scrubbing, washing away the relatively strong solution which remains on the strip with a relatively weaker solution, and removing the relatively weaker solution with rinsing sprays of water and thereafter drying the strip.

55 8. In the treating of strip metal to prepare it for the reception of a coating, the steps which comprise moving the metal strip in a substantially horizontal plane, and subjecting the strip while moving in this manner to a succession of operations performed in sequence as follows:

60 mechanically scrubbing the strip on both surfaces with hot water to remove solid particles and easily removed surface contaminations, dry- 70 ing the strip to prevent the carry-over of a film

75

of water beyond the drier, applying a relatively strong chemical solution to both surfaces of the moving strip to remove impurities and surface contaminations not removed by the scrubbing, washing away the relatively strong solution which remains on the strip with a relatively weaker solution, and removing the relatively

weaker solution with rinsing sprays of water and thereafter drying the strip, and heating and reusing the rinsing water, the dilute solution and the strong solution, some of the dilute solution being used in the preparation of the strong solution.

GEORGE M. CROFT.
